Primary Examiner — Robert M. Spear

(57) **CLAIM**

The ornamental design for an igniter for barbecue, as shown and described.

DESCRIPTION

1. Igniter for barbecue

1.1 : Unfolded

1.2 : Front view/back view

1.3 : Left

1.4 : Right

1.5 : Folded side view

1.6 : Folded front view

1.7 : Folded top view

The design represents an igniter for barbecue made of cardboard; the thin lines represent lines of folding of cardboard; no protection is sought for the features shown in broken lines.
